UNITED STATES PATENT OFFICE.

GEORGE ALLEN, OF SOUTH BEND, INDIANA.

DESIGN FOR A NUT-WRENCH.

57,068.

Specification for Design.

Patented Feb. 8, 1921.

Application filed May 14, 1920. Serial No. 381,479. Term of patent 14 years.

To all whom it may concern:

Be it known that I, GEORGE ALLEN, a citizen of the United States, residing at South Bend, in the county of St. Joseph and State of Indiana, have invented a new, original, and ornamental Design for Nut-Wrenches, of which the following is a specification, reference being had to the accompanying drawing, forming part thereof.

The figure is a plan view of a nut wrench, showing my new design.

I claim:

The ornamental design for a nut wrench, as shown.

GEORGE ALLEN.
